United States Patent Office.

MONTGOMERY P. SIMONS, OF PHILADELPHIA, PENNSYLVANIA.

Letters Patent No. 100,079, dated February 22, 1870.

IMPROVEMENT IN FAUCET-FILTERS.

The Schedule referred to in these Letters Patent and making part of the same.

I, MONTGOMERY P. SIMONS, of the city of Philadelphia, and State of Pennsylvania, have invented a new and useful Improvement in Faucet-Filters, of which the following is a specification.

The nature of my invention consists of a faucet having a filtering chamber in front of the key, and the latter having three-way openings constructed and arranged in relation to the main water passage, and a supplemental water way, in such a manner that by a certain adjustment of the key the said supplemental passage is closed, and the water passes through the main passage and is filtered; and when it becomes necessary to clean the filter the key may be turned so as to open the communication with the supplemental passage, and the main passage being also open with a full head of water at the same time the sediment seeks an outlet through the former, whereby the filter is cleaned. By another change in the position of the key the main and supplemental passages are closed.

In the accompanying drawings, which make a part of this specification—

Figure 1 is a side elevation of the improved faucet, partly in section.

Figure 2 is a cross-section at the line *a b* of fig. 1.

Figure 3 is a cross-section of the key through the openings 1 2 3.

Like letters in all the figures indicate the same parts.

A is the faucet, which has a main water passage, *a*, and a supplemental passage, *b*, the latter being used in cleaning out the settings from the filtering chamber *B*, as hereinafter described.

The said chamber has a perforated plate, *C*, through which the water passes so as to keep out large particles of foreign matter, and also hold the felt or other filtering media *D* in position against the gauze *E*.

F is a three-way key, a cross-section of which is shown in fig. 3.

G is the handle of the key.

When the filter is to be cleaned the key assumes

the position seen in figs. 1 and 2, the handle *G* being represented in full lines, the main openings 1 2 of the key being in line with the main passage *a*, and communicating with the contracted parts 1' 2', and the opening 3 being in communication with the supplemental passage *b* the water then washes the sediments so as to cause them to flow backward through the perforations *d* of the plate *C*, and through the supplemental passage *b* in their discharge from the faucet.

In drawing water through the faucet the key is turned one-half around, the handle *G* assuming the position represented by dotted lines. Then the solid part 4 of the key, as seen in fig. 3, closes the communication with the supplemental passage *b*. When the water is to be entirely cut off the key *F* is turned but one-fourth around, which brings the solid part 4 against the contracted passage 2'.

The water may be drawn for drinking and ordinary purposes both at the same time, if desired, when the handle *G* is in the position represented by full lines.

The faucet is made in two pieces *A* and *A'*, screwed together for the convenience of inserting the gauze piece *E*.

It will readily be seen that the faucet may be made with but little more expense than a common faucet, and presents the novel advantage of being cleaned without its removal from the water pipe.

What I claim as new, and desire to secure by Letters Patent, is—

A faucet having a supplemental passage *b*, a filtering chamber *B*, and a three-way key *F*, constructed and arranged in relation to each other substantially in the manner hereinbefore described.

In testimony that the above is my invention, I have hereunto set my hand and affixed my seal this 4th day of January, 1870.

MONTGOMERY P. SIMONS. [L. S.]
